Primary Examiner — Mary Ann Calabrese(74) *Attorney, Agent, or Firm* — Nath, Goldberg & Meyer; Jerald L. Meyer; Morgan D. Rosenberg(57) **CLAIM**

The ornamental design for a desk top, as shown and described.

DESCRIPTION

FIG. 1 is a perspective view of a desk top showing our new design;

FIG. 2 is a top view thereof;

FIG. 3 is a right side view thereof;

FIG. 4 is a left side view thereof;

FIG. 5 is a front view thereof;

FIG. 6 is a rear view thereof; and,

FIG. 7 is a bottom view thereof.

The broken line showing of the legs and leg attachments in FIGS. 1 and 3-7 illustrates environment that forms no part of the claimed design.

1 Claim, 7 Drawing Sheets(56)
